UNITED STATES PATENT OFFICE.

WALTER A. HALL AND CHARLES W. HALL, OF NEW YORK, N. Y., ASSIGNEES TO RAILWAY IMPROVEMENT COMPANY, OF NEW YORK, N. Y., A CORPORATION OF NEW YORK.

CONTROLLING DEVICE FOR COASTING-REGISTER MECHANISM FOR CARS OR TRAINS.

1,201,041.

Specification of Letters Patent.

Patented Oct. 10, 1916.

Application filed March 20, 1911. Serial No. 615,533.

To all whom it may concern:

Be it known that we, WALTER A. HALL and CHARLES W. HALL, citizens of the United States, residing in the city, county, 5 and State of New York, have made a certain new and useful Invention in Controlling Devices for Coasting-Register Mechanism for Cars or Trains, of which the following is a specification.

10 This invention relates to controlling devices for coasting register mechanism, that is for mechanism for registering the coasting or drifting period of cars or trains.

The object of the invention is to provide 15 controlling devices of the character, and for the purpose set forth, which are simple in construction and arrangement, and efficient in operation.

A further object of the invention is to 20 provide means controllable from the controller of the car or train motor for controlling the coasting register mechanism.

A further object of the invention is to 25 provide for the conjoint control of the coasting register mechanism by the car motor controller, and the brake mechanism of the car or train.

Other objects of the invention will appear 30 more fully hereinafter.

35 The invention consists substantially in the construction, combination, location and relative arrangement of parts, all as will be more fully hereinafter set forth, as shown in the accompanying drawing, and finally pointed out in the appended claims.

In the drawings:—Figure 1 is a view, somewhat diagrammatic, showing an arrangement embodying the principles of our invention. Fig. 2 is a broken detail view of 40 a modified arrangement of brake applying mechanism associated with the operation of and controlling the circuit of the coasting register device. Fig. 3 is a view showing a portion of the construction of recording 45 mechanism adapted for use in connection with our invention.

In the practical operation of street or other cars, railway trains or the like, after the operating power is shut off from the car 50 or train propelling motor in coming to a stop, the train or car coasts or drifts without any other propelling power than its own momentum. The time consumed during this coasting or drifting travel of the car or train

represents a saving of current or other power employed to operate the train or car. Registering devices or mechanism for registering the coasting or drifting period or travel of cars or trains, or the time consumed thereby have been devised and are now in extensive use. In the use of such devices and mechanism it is important that the registering operation be so controlled as to be put into action only when the current or other propelling power medium is shut off from the car or train propelling motors, and that it be arrested when the car or train completes its coasting or drifting travel. In accomplishing these and other objects we propose to provide means which are dependent upon the coasting or drifting travel of the car or train to effect the setting in operation of the coasting or drifting registering devices, and we also propose to combine therewith means for arresting the registering operation whenever current is turned on to the car propelling motor. We also propose to combine with such apparatus means whereby the registering operation, if in action, is arrested in case the car or train brake mechanism is applied.

In the drawing reference sign B, designates a portion of the coasting or drifting period registering mechanism in connection with which our invention is employed.

C, is a magnet arranged to control the starting and stopping of the registering mechanism. The circuit of magnet C, may be supplied with current from any suitable or convenient source which is controlled by the coasting or drifting movements or travel of the car or train. We have shown the circuit of magnet C, as being connected across the terminals of the armature of motor A, which may be one of the propelling motors of the car or train. The circuit connections 10, 11, are the controlling connections for controlling the propelling operations of the motor. From the motor armature, or rather from one side of the motor armature the circuit of magnet C, may be traced through connection 70 to a contact 71, thence through contact ring 72, to contact 73, wire 74, the coils of magnet C, wire 75, contact 76, bridging strip 77, contact 78, wire 79, contact 80, contact ring or segment 81, contact 82, wire 83, to the other side of the armature of motor A. The contacts 71, 73, are associated

with the contact ring or segment 72, which is connected with the propelling motor controller H, in such relation that when the controller is actuated from its completely 5 "off" position to its first step toward "on" position, the circuit between contacts 71, 73, is broken, and remains broken as long as the motor controller H, remains in any of its "on" positions. When, however, the controller H, is in its complete "off" position 10 the circuit of magnet C, is completed between the contacts 71 and 73. Similarly the contacts 80, 82, are controlled by a contact ring or segment 81, on the motor controller H, located at the other end of the car, in the usual manner.

The closing of the circuit of magnet C, between the contacts 71, 72, and also between contacts 80, 82, is necessary in order 20 for the registering mechanism to be put into operation. It is also necessary that the circuit of said magnet be closed between the contact points 76, 78, before the operation of the registering mechanism commences. But 25 the mere closing of the circuit of magnet C, at these points will not initiate any action of the register mechanism until the circuit of magnet C, is supplied with current. This current supply is afforded, as above stated, 30 from any suitable or desirable or convenient source, dependent, however, upon the coasting or drifting travel or movement of the car or train.

In the particular exemplification of our 35 invention shown in the drawing, where the circuit of magnet C, is connected across the terminals of the armature of the car or train propelling motor, the circuit of magnet C, receives current only when the propelling 40 motor A is operating as a generator. This condition obtains only when the train or car is coasting or drifting after current supply to motor A is shut off and the rotor of the motor is driven by the gearing which 45 connects it to the car axle, and it terminates when the coasting or drifting travel of the car or train is completed. In other words, the operation may be described as follows. Though, theoretically, the field of a motor 50 is considered to have little or no residual magnetism when the current thereto is shut off, in actual practice, it is impossible to obtain absolutely pure iron for the field magnets, and therefore, due to the impurities in 55 the iron, for one reason, there is invariably some residual magnetism in the field of the motor. This residual magnetism is sufficient to excite the field of the magnet so that upon continued rotation of the rotor of the 60 motor, the motor acts as a generator and the circuit 83, 79, 75, 70 connected across the terminals of the motor and closed only when the current to the motor is shut off, as hereinbefore explained, the current thus generated 65 flows through this circuit. In practice

we find that by winding the magnet C with a comparatively narrow gage wire the resistance of the magnet coil is sufficient to prevent the burning out of the armature of the motor for the purposes of our invention for 70 all speeds of cars or trains maintained while coasting, and at the same time, enables the magnet to operate the indicating device B at a very low voltage, or in other words, immediately upon the movement of the car or 75 train from standstill, if said movement is accomplished by gravity and not by power, for example, by releasing the brakes of the car or train at the top of a hill. Thus it will be seen that the action and operation of the 80 coasting or drifting registering mechanism is dependent not only upon the operation of the propelling motor as a generator, but also upon the motor controllers H, being in completely "off" position and also 85 upon the operation of the device which controls the bridging contact 77. This contact is carried by a stem 84, connected to a piston 85, operating in a cylinder 86, which is connected through a pipe or other connection 90, with the car or train air brake system, the arrangement being such that when the brake mechanism is applied the piston 85, is moved in a direction to move contact bridge 77, away from contacts 76, 78, thereby 95 breaking the circuit of magnet C.

In Fig. 2, we have shown a modified arrangement for use in connection with a hand brake system. In this arrangement we substitute for the contacts 76, 78, suitable fingers 100 88, 89, arranged to coöperate with a rod connected and associated with the hand brake apparatus and which is shiftable longitudinally coincidently with the operation of the hand brake. This rod has a portion 90, of 105 insulating material with which the fingers 88, 89, contact, when the hand brake mechanism is operated to apply the brake, thereby shifting said rod longitudinally in one direction, and a conducting portion 91, to 110 complete circuit connection between fingers 88, 89, when the hand brake mechanism is released and the rod is thereby shifted in the opposite direction.

Having now set forth the object and nature of our invention and arrangements embodying the principles thereof, what we claim as new and useful and of our own invention, and desire to secure by Letters Patent, is,

1. In an apparatus for registering the coasting or drifting travel of cars or trains, and in combination with the car or train propelling motor and brake mechanism, a registering mechanism, a controlling device therefor and means operated by the car propelling motor when acting as a generator, and under the control of the brake mechanism for operating the register controlling device.

2. In an apparatus for registering the coasting or drifting travel of cars or trains, and in combination with the car or train brake mechanism and propelling motor a registering mechanism, electrical devices for controlling the same, a circuit for said electrical devices, said circuit being connected across the terminals of the motor armature, contacts arranged in said circuit to be closed only when said motor controller is in "off" position, and contacts arranged in said circuit to be closed only when the car or train brake mechanism is in released condition.

3. In an apparatus for registering the coasting or drifting travel of cars or trains, and in combination with the car or train propelling motor and its controller, a registering mechanism, electrical devices for controlling the same, a circuit for said electrical devices, said circuit being connected across the terminals of the motor armature, and contacts arranged in said circuit to be closed only when said motor controller is in "off" position.

4. In an apparatus for registering the coasting or drifting travel of cars or trains, and in combination with the car or train propelling motor and its controller, and the train or car brake mechanism, a registering

mechanism, electrical devices for controlling the same, a circuit for said electrical devices, said circuit being connected across the terminals of the motor armature, contacts arranged in said circuit to be closed only when said motor controller is in "off" position, and other contacts also arranged in said circuit to be closed only when said brake mechanism is in released condition.

5. In a registering device of the character described, the combination with the car or train propelling motor and its controller, a circuit connected across the terminals of said motor, a registering device, means included in said circuit for operating said registering device, and means for closing said circuit only when the controller is in its off position.

In testimony whereof we have hereunto set out hands in the presence of the subscribing witnesses, on this 23d day of February A. D., 1911.

WALTER A. HALL.
CHARLES W. HALL.
